PATENTED
DEC 10 1867

Inventor:

Virgil Price

United States Patent Office.

VIRGIL PRICE, OF NEW YORK, N. Y.

Design No. 2,846, dated December 10, 1867.

DESIGN FOR A SET OF MASONIC BADGES.

The Schedule referred to in these Letters Patent and making part of the same.

TO ALL WHOM IT MAY CONCERN:

Be it known that I, VIRGIL PRICE, of the city, county, and State of New York, have invented a new and improved Original Design for a Set of Lodge-Jewels or Badges; and I do hereby declare that the following is a full, clear, and exact description thereof, which will enable others skilled in the art to understand the same, reference being had to the accompanying drawings forming a part of this specification, in which—

The figures from 1 to 10, inclusive, represent a face view of a set of blue-lodge badges or jewels.

Similar letters of reference indicate like parts.

This invention relates to a new method of ornamenting a set of badges or jewels worn by the officers of the Freemasons' lodges, and more particularly to those worn by the officers of the "blue lodge," and it consists in making the groundwork of officers' badges or jewels of the color appropriate to the rank of the lodge, and in arranging ornaments and borders on their surfaces of other suitable colors. The invention also consists in arranging upon the face of the badges or jewels the representations of corn, wine, and oil which are frequently referred to in Freemasons' lectures.

The badges or jewels are of the form appropriate to the rank of the officers by whom they are worn. Upon their faces are arranged branches, leaves, and grapes *a*, wheat-cars, *b*, and olive-branches, *c*, interlined with each other, Doric columns, *d*, the sun *e*, and Corinthian columns *f*, as shown in the drawings. The groundwork of the badges or jewels shown is blue.

Having thus described my invention, I claim as new, and desire to secure by Letters Patent—

The design for a set of lodge-jewels, herein described and set forth.

VIRGIL PRICE.
